UNITED STATES PATENT OFFICE.

JOSEPH H. COVERDILL, OF INDIANAPOLIS, INDIANA.

PLASTERING-MACHINE.

1,103,269.

Specification of Letters Patent. Patented July 14, 1914.

Application filed March 19, 1913. Serial No. 755,431.

To all whom it may concern:

Be it known that I, JOSEPH H. COVERDILL, citizen of the United States, residing at Indianapolis, in the county of Marion and State of Indiana, have invented certain new and useful Improvements in Plastering-Machines, of which the following is a specification.

This invention relates to improvements in plastering machines, and has primarily for its object the provision of such a machine arranged with a framework adapted to be held rigidly in position and having associated therewith moving trowel mechanism adapted to apply and spread the plaster upon the wall or other structure as desired.

A further object of the invention contemplates the provision of suitable mechanism whereby the plaster may be conveyed or removed from a source of plaster supply, lifted and dumped upon the trowel mechanism, and automatically applied and spread upon the wall or other structure to be acted upon.

A still further object of the invention resides in the provision of novel and peculiar trip mechanism arranged conveniently upon and in connection with the framework of the machine for automatically reversing the direction of travel of the trowel.

A further object of the invention is to provide means for actuating the conveyer mechanism, during the upward travel of the trowel for applying and spreading the plaster upon the wall, and for automatically stopping such mechanism during the reverse or downward travel of the trowel for only spreading and not applying the plaster to the said wall.

The invention further resides in the provision of means for simultaneously operating both the conveyer and trowel mechanism from one and the same source of motive power, such means being so arranged as to allow movement of either independent of the other.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying

drawings wherein like characters denote like or corresponding parts throughout the several views, and in which:

Figure 1 is a side elevation of a machine 60 constructed in accordance with my invention. Fig. 2 is a front elevation. Fig. 3 is a vertical sectional view. Fig. 4 is a top plan view. Fig. 5 is a detail elevation of the trowel supporting arm. Fig. 6 is a detail elevation of one of the chain links having a projection formed thereupon. Fig. 7 is a detail perspective view of the trip mechanism. Fig. 8 is an elevation of the reversing gears, and Fig. 9 is a detail elevation of one 70 of the said gears.

Proceeding now to the description of the drawings wherein is illustrated the preferred form of my invention the numeral 1 designates a pair of vertically extending 75 angle-irons, preferably U-shaped in cross section, to the lower extremity of which is secured base-irons 2, terminating in suitable framework 3, extending parallel with the irons 1 and connected thereto through the 80 medium of an angularly disposed frame portion 4, thereby constituting the entire framework or supporting structure of the machine.

Secured to the angle-irons 1 and extending throughout the length thereof and projecting beyond the top edge I provide 85 T-irons 5 having an angle-iron 6, U-shaped in cross section secured to the inner face thereof, the said angle-irons 6 adapted to support the trip mechanism, designated in its entirety by the numeral 7, a portion of the said trip mechanism fitting within a bulged portion 8 of the said T-iron 5, the detail construction of this particular feature being 90 hereinafter fully described.

A shaft 9 is journaled within suitable brackets 10 near the base of the vertically extending angle-irons 1, the said shaft having sprocket wheels 11 keyed or otherwise secured thereto near each end thereof, the 100 said sprocket wheels being connected to similar wheels 12 loosely mounted upon a shaft 13 journaled within bearings 14 mounted upon the upper extremity of the T-iron 5, and connected through the medium of 105 suitable chains 15. One link 16 of the said chain 15 is provided with a laterally projecting pin 17, formed integrally with the said link and fitting within a recess 18 formed within a head 19 secured to or 110 formed integrally with a shank 20 of the trowel supporting means. The said shank

20 is slidably mounted within a tubular member 21, the said sliding movement being limited by means of a pin 22 fitting within a slot 23 of the said tubular member, the said pin projecting from one face of the said shank 20. The tubular member 21 is secured to the trowel blade 24 by means of a plate 25, the said plate supporting the trowel blade in rigid relation to the said tubular member.

10 To yieldably support the trowel blade and to allow lateral movement of the pin 22, a suitable spiral spring 26 is interposed between the head 19 and the plate 25, thus supporting the trowel blade 24 as desired.

15 Each end of the trowel blade is provided with a roller 27 mounted upon a suitable bracket 28 as is clearly shown in Figs. 1 and 3 of the drawings. One of the said rollers 27 is normally inclosed by the angle-irons 6, the said angle-irons forming a track or rail upon and within which the roller runs or revolves. The spring controlled supporting means of the trowel, as above described is likewise provided with a roller 29

25 which also rides upon and within a track-way formed by the angle-irons 6, the roller 29 being spaced from the rear face of the trowel blade 24 a greater distance than the rollers 27 secured at each end thereof, there-

30 by supporting the said blade at an angle in the track or guide-way 6 and causing either the upper or lower edge of the blade to engage the wall or other structure upon which the machine is applying plaster, the tension

35 of the spring 26 forcing the blade against the said structure at all times, causing the blade to spread the plaster in the desired manner.

Smaller sprocket wheels 30 are secured to

40 a sleeve 30' through which the said shaft 9 extends and are likewise connected to sprocket wheels 31 mounted upon the upper shaft 13 by means of a second sprocket chain 32, the said chain 32 having a plurality of conveyer receptacles or brackets 33

45 secured thereto at predetermined spaced apart points throughout the entire length. The sprocket wheel 30 is mounted within, and the shaft 9 extends across, a suitable

50 hopper or plaster receptacle 34 rigidly mounted upon the frame base 2 for supplying the conveyer receptacles 33 with plaster as the same are conveyed by the travel of the chain 32 into the said receptacle. When

55 filled with plaster the conveyer receptacles 33 are carried upwardly from the lower sprocket wheel 30 and over the upper sprocket wheel 31 where they are tilted and finally dumped upon a suitable guide plate

60 or slide 35 normally supported at an angle to the chain 32 by means of an expansion spring 36, one end of the spring engaging the said plate 35 while the other end is secured to a laterally extending brace 37,

65 which forms a part of the framework of

the machine. By the above arrangement it will be seen that the conveyer receptacles 33 will empty or dump their contents upon the slide 35, the said slide guiding the material on to the trowel blade 34, where it is applied and spread to the wall or other structure acted upon. The provision of the spring 36 will allow the guide 35 to recede during the downward movement of the receptacles 33 as the same are brought into engagement therewith, and will in this manner no way interfere with the travel of the said receptacles according to the movement of the chain 32 to which they are attached.

Having described the operation of the conveyer, the detail construction of the means employed for controlling the movement thereof will now be described. An arm 38 is pivotally mounted upon one end of the lower shaft 9 of the machine and extends upwardly at an angle from the said pivot point and terminates in a head 39 having a slot 40 formed therein, the said slot limiting the pivotal movement of the arm 38. A stud shaft 41 is journaled within a suitable bearing 42 secured to the frame portion 3, the said shaft 41 extending through the said slot 40 and terminating at its outer end in a crank handle 43. A gear wheel 44 is keyed upon the said stud shaft 41 and rotated according to the movement of the said shaft caused by the turning of the handle 43. Another gear wheel 45 is secured upon a shaft 46 journaled within the arm 38, while a third gear wheel 47 is secured upon a third shaft 48 likewise journaled within the said arm, the said gear wheels 45 and 47 meshing as is shown in Fig. 1 whereby movement of either of the wheels is imparted to the other. By swinging the arm 38 upon its pivot either of the gear wheels 45 or 47 may be swung or brought into mesh with the gear wheel 44, thereby rotating the said gears according to the movement of the gear wheel 44. The shaft 46 upon which the gear wheel 45 is mounted has secured thereto at one end thereof a suitable sprocket wheel 49 connected to a sprocket wheel 50 through the medium of a chain 51 for rotating the shaft 9 upon which the said wheel 50 is mounted, according to the rotation of the shaft 46. The shaft 48 is likewise provided with a sprocket wheel 52 which is also connected to a suitable sprocket 53 by means of a chain 54, thereby rotating the sleeve 30', upon which the sprocket wheel 53 is mounted, according to the rotation of the said shaft 48. From the above construction it will be readily seen that the rotation of the shaft 41 will accordingly rotate the shaft 9 thereby operating the conveyer and the trowel mechanism above described. The sprocket wheel 53, driven by the shaft 48 through the medium of a chain 54, being rigid with the sleeve 30',

130

the said sleeve is rotated, such rotation imparting movement to the conveyer chains 15 by means of the sprocket wheels 30 which are likewise secured to the said sleeve 30', 5 while the sprocket wheel 30 which is driven by the rotation of the shaft 46 will simultaneously rotate the shaft 9 of the machine, thereby rotating the sprocket wheel 10 for operating the trowel mechanism connected 10 to the chain 15, this operation allowing the chains 15 and 32 to move or travel in opposite directions.

The lower gear wheel 47 has pivotally mounted upon one face thereof as at 55 a suitable pawl 56 adapted to engage a tooth rack 57 formed upon the said shaft 48, thus it will be seen that the wheel 47 is rotated when the shaft 46 is turned in one direction while the said wheel 47 will ride loosely 20 upon the shaft 48 during the turning of the shaft 46 in the opposite direction.

From the above description, it will be seen that the rotation of the wheel 44 will impart movement to the wheel 45 which will 25 in turn operate the trowel mechanism of the machine while the rotation of the wheel 47 will operate the conveyer mechanism of the machine. By shifting the arm 38 through the manipulation of a suitable lever 58 pivoted as at 59 to the frame, the lower gear wheel 47 is brought into mesh with the wheel 44, thereby allowing the said wheel 47 to turn independently of the shaft 48 upon which it is mounted, thus operating the 30 shaft 46 and the shaft 9 without rotating the sleeve 30', thereby operating the trowel chain 15 while the conveyer chain 32 is inoperative. This operation will permit the downward movement of the trowel mechanism 35 throughout the length of the beams 5 upon which it is mounted without operating the conveyer mechanism for conveying or lifting the plaster from the receptacle 34 and applying the same to the wall. As the 40 trowel mechanism reaches its uppermost point, the lever 58 is operated causing the conveyer mechanism to remain inoperative, and at the same time shifting or reversing the movement of the trowel mechanism and 45 allowing the same to travel downwardly and in engagement with the wall where it is again shifted upon reaching the lower extremity of the wall by again operating the lever 58, thereby causing the conveyer mechanism 50 to again operate for supplying plaster to the trowel during its upward movement.

Proceeding now to the description of the trip mechanism, the same preferably comprises a U-shaped bracket 60, slidably mounted within the bulged portions 8 of the T-irons 5, and upon the track beams 6, the said bracket 60 having ears 61 formed integrally therewith for the purpose of pivotally mounting as at 62, a trigger arm 63, having 65 a lug or projection 64 formed upon the inner

end thereof, normally held in engagement with the outer face of the bracket by means of a plate spring 65, secured as at 66 to the said bracket, at the upper end thereof. The vertical movement of the bracket 60, is 70

limited by the walls of the bulged portion 8 of the T-iron 5. An opening 67 is formed within the outer face of the U-shaped or track-beam 6 through which the rollers 27 pass so as to retain one of the said rollers 75 normally within the said track-way 6. The trigger mechanism 7, constructed in detail as above described is mounted adjacent the bulged portions 8 of the beams near the upper and lower extremities thereof to reverse the angle of the trowel blade 24 as the same is brought into engagement with the angular projections 68 of the track frame at the extremities thereof. The trowel mechanism when traveling along the track 80 in an upward direction comes in contact with the lower face of the bracket 60 causing the same to move upwardly so as to uncover the opening 67 of the track-way. The trowel mechanism when traveling along the track 85 in an upward direction comes in contact with the lower face of the bracket 60 causing the same to move upwardly so as to uncover the opening 67 of the track-way.

When in such raised position, the upper 90 roller 27 of the trowel is brought into engagement with the inclined portion 68 of the track-way causing the said trowel to swing upon the central roller 29 thereby forcing the lower roller 27 through the opening 67 95 whereupon the lever 58 is operated for reversing the direction of travel of the said trowel thus causing the trowel to travel downwardly along the wall or other structure acted upon. After passing through the 100 opening 67 the trip mechanism will fall into its normal position and the upper portion of the trowel blade is free to pass over the trigger arm 63 by reason of the pivotal connection afforded therefor as at 62. Any 105

suitable means such as a spring (not shown) may be employed for the purpose of returning the trigger mechanism 7 at the lower end of the beam. From the above taken in connection with the accompanying drawings 110 it will be seen that the reverse movement of the trowel is entirely controlled by the manipulation of the lever 58; that during the upward travel of the trowel mechanism the conveyer mechanism is operated for 115 supplying plaster to the said trowel and that by imparting reverse movement to the trowel mechanism, operation of the conveyer mechanism is instantaneously ceased thereby allowing the said trowel to travel downwardly throughout the length of the frame 120 where it is again reversed and the conveyer mechanism again operated; and that the provision of rollers such as are shown at 69 will permit transporting of the machine 125 from place to place as desired.

It will be understood that the above description and accompanying drawings comprehend only the general and preferred embodiment of my invention and that various 130

minor changes in the details of construction, proportion and arrangement of parts may be made within the scope of the appended claims and without sacrificing any of the advantages of my invention.

Having thus fully described my invention, what I claim as new and desire to secure by Letters Patent, is:—

1. A plastering machine including a frame, reciprocable trowel mechanism carried by said frame adapted to travel throughout the length thereof, means for reversing the direction of travel of the said trowel mechanism as it reaches the extremities of the said frame, conveyer mechanism carried by said frame adapted to feed the plaster on to the said trowel, and means for operating the trowel mechanism independent of the said conveyer mechanism.

2. A plastering machine including a trowel, means for moving said trowel, and means independent of the said first mentioned means for automatically shifting the position of said trowel at predetermined points during its movement.

3. A plastering machine including a trowel, means for reciprocating said trowel, and means independent of said first mentioned means for automatically shifting the position of said trowel at each end of its reciprocating stroke.

4. A plastering machine including a trowel, means for reciprocating said trowel, means normally maintaining said trowel at an angle to the surface acted upon, and means automatically shifting the position of said trowel at each end of its reciprocating stroke.

5. A plastering machine including a trowel, means for reciprocating said trowel, a guide therefor, trip mechanism arranged at each end of the said guide, said mechanism being engageable with the said trowel to automatically shift the position thereof, as and for the purpose set forth.

6. A plastering machine including a reciprocable trowel blade, the said blade adapted to be normally maintained at an angle to the surface acted upon, guide means for the trowel, and trip mechanism arranged at the respective ends of the said guide means, the said trip mechanism being disposed for engagement with the said trowel to automatically shift the position of the latter at each end of its reciprocating stroke.

7. A plastering machine including a trowel, means for reciprocating said trowel, guide means therefor, trip mechanism arranged at each end of said guide, said trip mechanism being disposed in the path of said trowel, means maintaining said trowel at an angle to the surface acted upon, and means carried by the said guide and disposed for engagement with said trowel to automatically shift the angular position of

the latter when engaged by said trip mechanism, as and for the purpose set forth.

8. A plastering machine including a trowel, means for reciprocating the trowel, means maintaining said trowel at an angle to the surface acted upon, means reversing the direction of travel of said trowel, and trip mechanism automatically shifting the angular position of said trowel simultaneously with the actuation of said reversing means, as and for the purpose set forth.

9. A plastering machine including a frame, trowel mechanism carried by said frame, means for reciprocating said mechanism, means for reversing the direction of travel of said mechanism, conveyer mechanism carried by said frame adapted to feed the plaster on to the said trowel mechanism, and means carried by said frame for operating said conveyer mechanism during the movement of the trowel in one direction only, as and for the purpose set forth.

10. A plastering machine including a trowel, means for reciprocating said trowel, conveyer mechanism for feeding plaster to said trowel, independent means automatically shifting the position of the trowel at each end of its reciprocating stroke, and means actuating said conveyer mechanism to operate the latter only through the movement of the trowel in one direction, as and for the purpose set forth.

11. A plastering machine including a trowel, means for reciprocating said trowel, guide means therefor, trip mechanism carried by the said guide means and disposed for engagement with said trowel to automatically shift the position of the latter at each end of its reciprocating stroke, conveyer mechanism for feeding plaster to the said trowel, and means for operating the said conveyer mechanism only during the movement of the trowel in one direction, as and for the purpose set forth.

12. A plastering machine including a frame, mechanism including a trowel blade carried by said frame, means reciprocating said mechanism throughout the length of said frame, a guide for said mechanism, trip mechanism positioned at the respective ends of said guide, said trip mechanism automatically reversing the position of said trowel blade at each end of its reciprocating stroke, conveyer mechanism carried by said frame, said mechanism automatically feeding the plaster on to the said trowel during its movement in one direction, and means for operating said conveyer mechanism and said trowel mechanism simultaneously from the same source of power, as and for the purpose set forth.

13. A plastering machine including reciprocable trowel mechanism, conveyer mechanism associated therewith, means for simultaneously actuating the said conveyer

mechanism and the said trowel mechanism from the same source of power, and means whereby the said trowel mechanism is operated independent of the conveyer mechanism during its movement in one direction, as and for the purpose set forth.

14. A plastering machine including reciprocable trowel mechanism including a trowel blade, conveyer mechanism associated therewith, guide means positioned over said blade for conveying the plaster acted upon thereonto, means for actuating said trowel mechanism and said conveyer mechanism simultaneously from the same source of power, and means whereby said trowel mechanism may be moved independent of said conveyer mechanism during one of the reciprocative strokes of the former, as and for the purpose set forth.
15. A plastering machine including a reciprocable trowel, guide means therefor, trip mechanism arranged at the respective ends of the said guide means and disposed for engagement with the said trowel to automatically shift the position of the latter at each end of its reciprocative stroke, conveyer mechanism operable in connection with the said trowel, means for simultaneously actuating the said conveyer and the said trowel and means for moving said trowel independent of the conveyer mechanism during one of the reciprocative strokes of the former, as and for the purpose set forth.

16. A plastering machine including a frame, reciprocable trowel mechanism carried by said frame adapted to travel throughout the length thereof, guide means for the said trowel mechanism, trip mechanism arranged at the respective end of the said guide means and disposed in the path of the said trowel mechanism to automatically shift the position of the latter at each end of its reciprocative stroke, means for reversing the direction of travel of the trowel mechanism as it reaches the extremity of the said frame, conveyer mechanism carried by said frame adapted to feed the plaster on to the said trowel and means for operating the trowel mechanism independent of the said conveyer mechanism during one of the reciprocative strokes of the former, as and for the purpose set forth.

17. A plastering machine including frame, a reciprocable trowel mechanism including a trowel blade carried by said frame, conveyer mechanism operable in connection with said trowel mechanism, means for simultaneously operating the said trowel mechanism and the said conveyer mechanism, and means including a spring actuated guide member positioned at one end of the said conveyer mechanism, the said guide member being disposed for engagement therewith to guide the plaster acted upon on to the trowel blade during

one of its reciprocative strokes, as and for the purpose set forth.

18. A plastering machine including a frame, reciprocable trowel mechanism including a trowel blade carried by said frame, conveyer mechanism operable from the same source of power as the said trowel mechanism, means for operating said trowel mechanism during one of its reciprocative strokes independent of the said conveyer mechanism, a spring actuated guide member arranged at one end of the said conveyer mechanism, the said guide member being positioned above the said trowel mechanism to guide the plaster acted upon on to the said blade, as and for the purpose set forth.

19. A plastering machine including reciprocable trowel mechanism including a trowel blade, guide means therefor, trip mechanism disposed at the respective ends of the said guide means in the path of the said trowel blade for shifting the position of the latter at each end of its reciprocative stroke, conveyer mechanism operable in connection with the said trowel mechanism, means actuating the said trowel mechanism and the said conveyer mechanism from one and the same source of power, means operating the said trowel mechanism during one of its reciprocative strokes independent of the said conveyer mechanism, and means including a spring actuated guide member arranged at one end of the said conveyer mechanism and above the said trowel mechanism for guiding the plaster acted upon on to the trowel blade, as and for the purpose set forth.

20. In a plastering machine, the combination with a trowel and means for reciprocating said trowel, guide means therefor, a support member arranged at each end of the said guide means, a trip arm pivoted to the said support, the said trip arm being disposed for engagement with the said trowel during its reciprocating movement, means arranged at each end of the said guide for automatically shifting the position of the said trowel, the said trip arm adapted to be actuated simultaneously with the shifting of the said trowel, as and for the purpose set forth.

21. In a plastering machine, the combination with a trowel and means for reciprocating the said trowel, guide rails therefor, a support member arranged at each end of said guide rails, a trip arm pivoted to said support, said trip arm being disposed for engagement with the said trowel during its reciprocating movement, an angular extension formed upon each rail at their respective ends, the said extensions being engaged by the said trowel for automatically shifting the position of the same, the said trip arm adapted to be actuated simultaneously

- with the shifting of the said trowel, as and for the purpose set forth.
22. In a plastering machine, the combination with a trowel and means for reciprocating said trowel, guide rails therefor, each rail being enlarged at one end thereof, the said rails being cut away adjacent each enlargement, a sliding support member arranged within the enlarged portion of each rail, a spring pressed trip arm pivoted to said support, the said trip arm being disposed in the path of the said trowel, the said support being disposed to normally close the opening formed by the said cut away portion of the rail, an angular extension formed at each end of said rails, the said extensions being disposed for engagement with the said trowel mechanism to automatically shift the position of the latter at each end of the reciprocating stroke, a portion of the said trowel adapted to pass through the said openings when uncovered by the movement of the said trip mechanism, as and for the purpose set forth.
23. In a plastering machine, the combination with a trowel and means for reciprocating said trowel, conveyer mechanism associated therewith, a spring actuated guide member arranged at one end of the said conveyer mechanism, the said guide member being normally maintained at an angle to the vertical axis of the said conveyer mechanism, one end of the said guide member being disposed in the path of the said conveyer, the said guide member being disposed above the said trowel mechanism, to guide the plaster acted upon from the said conveyer on to the said trowel, as and for the purpose set forth.
24. In a plastering machine, the combination with a trowel, means for reciprocating said trowel, conveyer mechanism operable in connection therewith, an endless element to which the said trowel is secured, and means for shifting the direction of travel of said element at each end of the reciprocating stroke of the trowel, as and for the purpose set forth.
25. In a plastering machine, the combination with a trowel blade, an endless element, a pin projecting laterally from the said element, and means yieldably connecting the said pin with the said blade to support the latter, as and for the purpose set forth.
26. In a plastering machine, the combination with a trowel blade, a plurality of rollers mounted thereupon, a sleeve projecting from one face of the said blade, a stem slidably maintained within the said sleeve, an endless element to which the stem is connected, and spring means interposed between the said blade and the said element to form a cushion support for the former, as and for the purpose set forth.
27. In a plastering machine, the combination with a trowel and means for reciprocating said trowel, a sleeve projecting from one face of said trowel, a stem slidably maintained within the said sleeve, a head formed upon one end of said stem, an end less element for driving the said trowel, a pin projecting from said element, said pin adapted to fit an opening provided therefor within said head, and a spring arranged to embrace said sleeve and to engage the said trowel and the said head to provide a cushion support for the former, as and for the purpose set forth.
28. In a plastering machine, the combination with a trowel and means for reciprocating said trowel, a guide rail therefor, rollers carried by the said trowel, one of the said rollers being at all times disposed for engagement with the said rail, and trip means carried by the said rail and disposed for engagement with the said trowel to automatically shift the position of the latter to bring one or the other of the rollers into or out of engagement with the said rail, as and for the purpose set forth.
29. In a plastering machine, the combination with a trowel and means for reciprocating said trowel, guide means therefor, a roller carried by the said trowel adapted to be at all times disposed for engagement with the said guide means, other rollers carried by the said trowel, the said rollers being disposed at the end thereof, trip mechanism arranged at the respective ends of the said guide means and disposed for engagement with the said trowel to shift the position of the latter at each end of its reciprocative stroke, the said last mentioned rollers adapted to be swung either into or out of engagement with the rails to maintain the said trowel at an angle thereto during the engagement between the said trowel and the said trip mechanism, as and for the purpose set forth.
30. In a plastering machine, the combination with a portable frame, a trowel carried thereby, means for reciprocating said trowel, a conveyer associated with the said trowel, a pivoted arm supported by the said frame, and means carried by the said arm for actuating the said trowel and the said conveyer simultaneously or the said trowel independent of the said conveyer, as and for the purpose set forth.
31. In a plastering machine, the combination with a portable frame, a trowel carried by the said frame, means for reciprocating said trowel, an endless conveyer carried by the said frame, an endless element to which the said trowel is connected, an operating shaft to which the said endless conveyer is arranged, a sleeve carried by the said conveyer over which the said endless element is arranged, an arm pivoted to the said shaft,

mechanism carried by the said arm and connected respectively with the said shaft and with the said sleeve for either simultaneously operating the said endless element and the said conveyer or for actuating the said element independent of the conveyer, as and for the purpose set forth.

32. A plastering machine including a frame, a trowel reciprocably mounted upon said frame, and adapted to travel throughout the length thereof, trip mechanism carried by said frame for reversing the position of the trowel, conveyer mechanism carried by said frame for feeding plaster on to the trowel and means including a plurality of gears carried by said frame for reversing the direction of travel of the said trowel mechanism and for allowing the same to operate independently of the conveyer mechanism.

33. A plastering machine including a frame, a trowel reciprocably mounted upon said frame and adapted to travel throughout the length thereof, conveyer mechanism carried by said frame adapted to feed plaster on to the said trowel during the upward travel thereof, trip mechanism mounted upon each extremity of the said frame for reversing the position of the trowel as it moves into engagement therewith, and means carried by said frame for reversing the direction of travel of the trowel and for operating the same independently of the conveyer mechanism during the downward travel of the trowel.

34. A plastering machine including a frame, a reciprocable trowel adapted to travel throughout the length of said frame, trip mechanism for reversing the position of the trowel as the same moves into engagement therewith, conveyer mechanism carried by said frame for feeding plaster on the trowel during the upward travel thereof, a plurality of gears carried by said frame and connected to the said trowel and conveyer mechanism and means for operating said gears for reversing the direction of travel of the said trowel and for allowing the same to operate independent of the conveyer mechanism during the downward travel of the said trowel.

35. A plastering machine including a frame, reciprocable trowel mechanism including a trowel blade adapted to travel throughout the length of said frame, trip mechanism mounted at the extremities of said frame for reversing the position of the said blade as the trowel mechanism moves into engagement therewith during its travel throughout the length of the frame, conveyer mechanism carried by said frame for feeding plaster on to the trowel during the upward travel thereof, an arm pivotally mounted to the said frame, a plurality of gears carried by said arm, the said gears being connected to the trowel mechanism

and the conveyer mechanism, and means for operating the said arm for shifting the gears for reversing the direction of travel of the trowel mechanism and allowing the same to operate independently of the conveyer mechanism.

36. In a plastering machine, the combination of a frame, a track-way formed by the said frame, trowel mechanism carried by said frame, the said trowel mechanism having rollers adapted to operate upon the said track, of chain and sprocket mechanism carried by said frame, said trowel mechanism being connected to the said chain for operating the trowel according to the movement of the chain and means including a plurality of gears carried by said frame for reversing the direction of travel of the said chain for reciprocating the trowel mechanism upon the said frame.

37. In a plastering machine, the combination of reciprocable trowel mechanism including a blade, a tubular member upon which said blade is mounted, a shank slidably mounted within the said tubular member and means for limiting the said sliding movement of the said shank, of chain and sprocket mechanism carried by said frame, a projection formed upon the said chain, the said projection adapted to be secured to the said shank for operating the trowel mechanism according to the direction of travel of the said chain, and means including a plurality of gears carried by the said frame for reversing the direction of travel of the said chain.

38. In a plastering machine, the combination of a frame, reciprocable trowel mechanism carried by said frame, the said mechanism including a trowel blade having rollers secured to each end thereof, one of which is adapted to fit within the said frame, a tubular member secured to said blade, a shank slidably mounted within the said tubular member, means for limiting the movement of said shank, a head formed integrally with said shank, and a roller carried by said head adapted to fit within the said frame for disposing the trowel blade at an angle thereto. of sprocket and chain mechanism carried by said frame, a projection formed upon said chain, the said projection adapted to fit within a recess formed within the said head for imparting movement to the said trowel mechanism according to the movement of the said chain and means including a plurality of gears carried by said frame for reversing the direction of travel of the said chain for reciprocating the trowel mechanism.

39. In a plastering machine, the combination of a frame, trowel mechanism including a trowel blade reciprocably mounted upon said frame, a track-way formed by the said frame extending throughout the length

thereof, rollers carried by said trowel mechanism adapted to fit within said track-way, one of said rollers being spaced from the trowel blade for disposing the same at an 5 angle to the said track and an angle plate formed upon the extremities of the said track, of trip mechanism slidably mounted upon the said track for normally closing an opening formed therein, a bulged portion 10 formed adjacent the said track for limiting the sliding movement of the said trip mechanism, means for reciprocating the trowel mechanism, the angle of the said trowel blade adapted to be reversed as it is brought 15 into engagement with the said trip mechanism for allowing the same to travel in one direction at an angle opposite to that assumed when traveling in the other direction.

40. In a plastering machine the combination 20 of a frame, vertically extending tracks supported by said frame, trowel mechanism including a trowel blade reciprocably mounted and adapted to travel throughout the length of said track-ways, a plurality of 25 rollers carried by said trowel mechanism, certain of which are adapted to fit within the said track-way for disposing the trowel blade at an angle thereto, angle plates formed integrally with and upon the extremities 30 of the track-way for reversing the position of the trowel blade as the trowel mechanism moves into engagement therewith, a bracket slidably mounted upon the track-way, the movement of the said bracket being 35 limited by a bulged portion formed within the said frame, the said bracket adapted to normally close an opening formed within the said track-way, a spring controlled trigger arm pivotally mounted to the said 40 bracket, the said trowel mechanism adapted to raise the said bracket, the said trowel at the same time engaging the said angular plate for reversing the position of the blade and forcing one of the rollers through the 45 said opening of the track-way, and means for reciprocating the trowel mechanism throughout the length of the track-way as and for the purpose set forth.

41. In a plastering machine, the combination 50 of reciprocable trowel mechanism including a trowel blade adapted to travel vertically throughout the length of the machine, means for reversing the position of the blade upon reaching the extremities of 55 the machine, conveyer mechanism carried by the machine for feeding plaster on to the trowel during upward travel thereof, a plaster receptacle carried by the machine for supplying the conveyer mechanism with 60 plaster as it travels therethrough and means including a plurality of gears carried by the machine and connected to both the trowel and conveyer mechanism for operating them simultaneously or the trowel mechanism independent of the conveyer.

42. In combination with a plastering machine, a frame having a track-way extending throughout the length thereof, vertically reciprocable trowel mechanism including a trowel blade supported by said track-way, 70 trip mechanism carried by said track-way for reversing the position of the trowel as the same is brought into engagement therewith, a plaster receptacle carried by said frame at the base thereof, conveyer mechanism mounted upon said frame extending from the said receptacle to the top of the track-way for conveying plaster and feeding the same on to the trowel during the upward travel thereof, means for guiding the plaster 75 on to the trowel and means carried by the frame for operating the trowel mechanism independent of the conveyer for allowing the said trowel to travel while the conveyer is inoperative.

43. In combination with a plastering machine, a frame, vertically extending track-ways carried by said frame, reciprocable trowel mechanism including a trowel blade adapted to travel throughout the length of 90 said track-ways, means for reversing the position of the trowel at the extremities of the said track-ways and means extending throughout the length of the track-ways for reciprocating the said trowel mechanism, of a plaster receptacle, conveyer mechanism extending throughout the length of the track-ways adapted to convey plaster from the said receptacle on to the trowel mechanism during the upward travel thereof, of spring 100 controlled means for guiding the plaster from the said conveyer on to the said trowel and means including a plurality of gears mounted upon said frame for simultaneously operating both the conveyer and trowel mechanism and for operating the trowel mechanism independent of the conveyer to allow downward travel of the trowel while the conveyer is inoperative.

44. In combination with a plastering machine, vertically extending track-ways carried by said machine, reciprocable trowel mechanism including a trowel blade mounted upon said track-ways and adapted to travel throughout the length thereof, trip mechanism at each end of the said track-ways for reversing the position of the trowel as the same is brought into engagement therewith, and means including chain and sprocket mechanism for reciprocating the said trowel, of a plaster receptacle supported upon the base of the machine, an endless conveyer mounted upon the frame and extending throughout the length thereof, the said conveyer adapted to convey plaster from the said receptacle to the top of the machine where it is dumped on to the said trowel mechanism, a spring controlled guide-plate supported by the machine for guiding the plaster during the dumping opera- 120 125 130

tion, and means including a plurality of gears mounted upon the machine for simultaneously operating both the trowel and conveyer mechanism or the trowel mechanism 5 independent of the conveyer during the downward travel of the said trowel.

45. In a plastering machine, the combination of reciprocable trowel mechanism including a trowel blade, an endless conveyer 10 carried by the machine and means for reversing the position of the trowel at each end of the machine, of an arm pivotally connected to the machine, a stationary gear mounted upon the machine and a pair of 15 gears mounted upon the pivoted arm adapted to be swung so as to bring one of the said gears into mesh with the said stationary gear for operating the said trowel and conveyer mechanism simultaneously or the 20 said trowel mechanism independent of the said conveyer mechanism.

46. In a plastering machine, the combination of a frame, vertically extending trackways carried by said frame, reciprocable 25 trowel mechanism including a trowel blade carried by said track adapted to travel throughout the length thereof, trip mechanism mounted upon each end of the trackway for reversing the position of the trowel 30 as the same is brought into engagement therewith, chain and sprocket mechanism for reciprocating the trowel, and means for attaching the said trowel mechanism to the said chain and sprocket mechanism, of a 35 plaster receptacle mounted upon the base of the machine, an endless conveyer extending throughout the length of the machine for conveying plaster from within the receptacle on to the said trowel mechanism during the 40 upward movement thereof, a spring controlled guide-plate for guiding the plaster on to the trowel mechanism after leaving the conveyer, an arm pivotally mounted upon the frame, a stationary gear mounted 45 upon the frame, the said gear being connected to the said pivoted arm, a pair of gears mounted upon the said arm, and means

including a pivoted lever carried by said arm for swinging the same so as to bring one of the said gears into mesh with the said stationary gear for operating the trowel and conveyer mechanism or for operating the trowel mechanism in a downward direction independent of the conveyer mechanism. 50

47. A plastering machine including a trowel, an endless element upon which the said trowel is mounted for movement, and means shifting the position of said trowel relative to said element, as and for the purpose set forth. 55

48. A plastering machine including a trowel, an endless element upon which the trowel is mounted, means for operating said element, means normally maintaining said trowel at an angle to the surface acted upon, and means automatically shifting the position of said trowel relative to said element, as and for the purpose set forth. 60

49. A plastering machine including a trowel, an endless element to which the trowel is connected, means actuating said element, means for reversing the direction of travel of said element at predetermined intervals, and means for shifting the trowel 75 relative to said element simultaneously with the reversing operation, as and for the purpose set forth. 70

50. A plastering machine including a trowel, an endless element to which the trowel is connected, means for operating said element, means for reversing the direction of travel of said element whereby to impart to said trowel a reciprocatory movement, and trip mechanism engageable with said trowel 80 at each end of its reciprocating stroke to shift the said trowel relative to said element, as and for the purpose set forth. 85

In testimony whereof I affix my signature in presence of two witnesses.

JOSEPH H. COVERDILL.
